ROVING FRAME CONE

Fay H. Martin, West Newton, Mass.

Application October 27, 1932, Serial No. 639,829

10 Claims. (Cl. 118—33)

This invention relates to the paired cones which form an essential part of roving frames and serve as a variable speed mechanism to transmit to the bobbins a speed of rotation in excess of that of the flyer, in the usual bobbin-lead fly frames, which excess speed is known as the winding speed of bobbin rotation. As is well-known, the cones are mounted in parallel and reversed relation, the top cone being driven and imparting driving rotation to the bottom cone by a narrow belt or other interposed frictional driving device which is shifted lengthwise of the cones step by step by the rack motion of the tension devices of the frame at the end of the winding of each layer of roving on the bobbin, to compensate for the increased diameter of the bobbin as a result of the winding of such layer and thus to reduce the rate of axial winding rotation of the bobbin to keep the peripheral speed of the wound mass constant and in proper accord with the rate at which the roving is delivered from the drawing rolls.

Any discrepancies between the rate of delivery and the rate of winding-on of the roving result in a change in the tension, which if too tight draws and thins and weakens the roving in uncontrolled manner, or if too slack permits it to contract and thicken under the twist being inserted so that it becomes oversized, either contingency resulting in serious troubles rendering it difficult or impossible to obtain the essential degree of uniformity in the product.

The paired cones which are thus used to provide the variable speed drive of the bobbins have all been designed on the presumption that the winding of each successive layer of roving adds a constant amount to the diameter of the wound mass, irrespective of the position of such layer in the sequence of layers from the beginning to the end of the winding, as would be true in winding wire or other unyielding substance. The underlying mathematical relationship between the whole and the part added, where the part added remains constant and is added to the whole over and over again is expressed in the curve known as the hyperbola. Thus this curve forms the basis for the shaping of all known pairs of roving cones, the values of the curve being divided between the two complementary cones at equivalent points to keep the slope of each as gentle as possible for the sake of the belt drive, all as known.

It is well-known that in practice these hyperbolic cones, or more properly conoids, do not actually provide a rate of change in the winding speed that will keep the tension correct throughout the winding of a set of bobbins from empty to full

relation. Thus, with the best possible adjustment of twist, tension, and lay, with all related mechanism in the best of mechanical condition, such conspicuous discrepancies in the tension regularly arise in the course of the winding as to make it standard practice for the attendant to stop the frame, lift the knock-off latch and move the belt shifter rack by hand in the attempt to reestablish approximately correct relationships. This process of racking is resorted to whenever the need becomes apparent to the operator's eye or touch, ordinarily occurring once or several times in winding each set of bobbins. Such need for constant supervision and manual adjustment of the tension to supplement the mechanical or automatic control supposed to be effected by the cones is a serious obstacle to production both through cutting down the number of frames an operator can properly attend, and through requiring stoppage of the spinning while the adjustment is being made, and is further objectionable through causing bad work if the adjustment be improperly made. In the effort to avoid this objectionable necessity for racking, uniformity in the roving has been sacrificed through inserting an excess twist and tension, which method has its own drawbacks, perhaps the worst of which is the inevitable cutting down of the production which comes from slowing down the drawing rolls to secure this increased twist.

I have discovered that with the best possible adjustments and conditions there is an unfailing tendency for the tension to become too slack at a stage early in the winding when the latter is effected by theoretically correct hyperbolic cones, this slackness becoming conspicuous after 15 to 20% of the thickness of the finished bobbin has been wound. This departure from proper tension unavoidably introducing permanent unevenness, may leave its effect on the roving through continuing as slack tension clear through to the completion of the winding, or may result in a more or less orderly alternating sequence of successively thin and thick layers of roving being wound.

I have found that the varying pressure of the presser is probably the most important factor in effecting the growth of the bobbin so as to throw it out of step with the theoretical rate of growth on which the use of the hyperbolic cones is predicated. This factor has been totally disregarded so far as I am aware in designing all known roving cones, because uniformity of strand-thickness has been taken for granted. Yet this pressure varies within rather wide limits during the building-up of the bobbin, being

at its maximum when the first layer is wound on the bobbin and being at its minimum when the last or outermost layer is wound, as will be plain from the diagram of Fig. 6. Apparently because of the resistance to compression of the first few layers wound, which results from their proximity to the hard and unyielding surface of the bobbin, the forces such as that of the presser which throw the bobbin size out of step with the hyperbolic cones do not have an observable effect at first; but their action becomes increasingly apparent after the first 10% or 15% of the thickness of the bobbin has been wound, resulting in a gradual compacting or condensing of the wound layers which reduces the diameter of the bobbin below the theoretical size and accordingly produces a cumulative slackness of tension. As is well-known, this slackness usually attains its maximum when about 30% of the bobbin has been wound. It is to be noted in this connection that these several stages which have been approximately indicated by the percentages of thickness given, are substantially constant for all sizes of bobbins and of roving being wound, because as constructed the relationship of the presser to its flyer remains substantially constant regardless of the size of the flyer, which varies in accordance with the size of the full bobbin being wound therewith. It is this constancy of relationship which makes it possible to formulate corrections which are applicable to all types of cones employed in roving frames.

An important feature relating to the practice of my invention is my discovery that when the slackness commonly known to occur during the winding of the earlier portions of the thickness of a bobbin has been corrected through modifying the shape of the cones, the excessive tension also commonly arising at the finish of the winding does not occur. The practical importance of this is that while I reduce the diameter of portions of the cones at points intermediate their length, (because a slack tension means that the bottom cone is too large and hence is being driven too slowly if it produces a slack tension,) yet I do not have to exceed the diameter of the true hyperbolic cones at any point and especially at the big end of the bottom cone, in order to keep the tension uniform throughout and to prevent the customary excessively tight tension at the end of the winding which follows as a consequence of intermediate slack tension, and which otherwise would seem to call for an increase in the diameter of the big end of the bottom cone. Thus I am enabled to apply the principles of my invention to the reshaping of existing roving cones of whatever make or design, applying my improvement thereto by a simple machining operation involving only the removal of a portion of the metal, and without the need to scrap and replace one or both of the old cones, with obvious practical advantage and economy.

A further advantage of the invention is that the modifications contemplated may all be effected through an alteration of the bottom cone alone; this bottom cone is far more easily removed and replaced in the roving frame than the top cone, the change being merely the matter of a few minutes' work.

The invention in its broadest aspect comprises a cone controlling the winding speed of a bobbin, having intermediate portions of its length of a diameter less than the diameter needed to im-

part a progressive reduction in bobbin rotation as based on the presumption of equal additions to bobbin diameter as produced by winding the successive layers. Preferably, the improved cone will comprise a series of contiguous conical frusta, so as to simplify the mechanical operations involved in its making, instead of the hyperbolic conoidal form heretofore employed. This cone will have a belt engaging surface less in diameter at substantially all points in its length than that of the hyperbolic conoid conforming to the theoretical percentage of increase in bobbin diameter.

An illustrative embodiment of the invention is shown in the accompanying drawings, in which,—

Fig. 1 shows the paired cones as used in a roving frame, the bottom cone of the invention being shown in full lines within the standard equivalent true hyperbolic cone, which is indicated in dotted lines.

Fig. 2 shows certain steps in performing the actual operations of making the improved cone.

Fig. 3 is a large scale showing of a portion of Fig. 2 at the top center of the latter.

Fig. 4 is a hyperbola showing the theoretical rate of increase of bobbin diameter.

Fig. 5 shows a standard flyer in operating relation to its empty bobbin, with a full bobbin indicated in dotted lines.

Fig. 6 is a diagram illustrating the variation in the pressure of the presser as the bobbin increases in diameter.

One good way of carrying the invention into effect is as follows:

Since the invention is aimed to correct and improve the operation of roving frame cones, whose fundamental law of winding in layers is represented by a hyperbola, the casting (if a new cone) or the old roving frame cone, as the case may be, is first divided equally into 35 stations, of which the small extremity is station zero and the large end is station 35, this because 35 inches is the usual length of the standard cones. Then the dimensions of the theoretical hyperbola g are applied to the casting or the cone at stations 0, 5, 25, and 35, as through cutting annular grooves to the proper depth so that their bottoms lie in the curve of the hyperbola and of sufficient width to operate in, on the order of $\frac{1}{4}$ inch, it being understood that this basic hyperbola is calculated with respect to the complementary top cone, to which a cooperating hyperbolic curvature will have been given, as referred to herein before. Where the cones to be corrected have true hyperbolic outline, this grooving to apply the hyperbola is unnecessary, as in the case of Figs. 1, 2 and 3.

Starting with the diameter found or thus arrived at at the bottom of the annular groove at station 0 the material of the cone may be cut away on a straight taper such as will exactly coincide at station 5 with the diameter found on the true hyperbolic cone, or in other cases applied as above to the cone at the bottom of the annular groove here. In other words, this first operation produces a section extending from station 0 to station 5 which is a true conic frustum, having for its slope a single straight line, as distinct from the conoidal frustum of the true hyperbolic cone, of which the profile is not a straight line but a curve. As explained later, this step is optional in correcting old cones, unless desired to counteract belt-slippage.

A similar straight taper is next applied to the

cone or casting in such manner as to have at its small end this exact diameter of the true hyperbolic cone or of the bottom of the annular groove at station 5, as the case may be, and 5 at its large end the exact diameter of the true hyperbolic cone, or in other cases, of the cone at the bottom of the groove, at station 25, the beginning and end of such cut and of the straight lines denoting its course being indicated by the 10 encircled numeral 1 in Figs. 2 and 3. As before, this straight taper, intersecting the theoretical hyperbola at stations 5 and 25, as indicated at *a* and *b* in Figs. 2 and 3, gives to this section of the cone the form of a true conic frustum.

15 Another straight taper is begun at station 21, intersecting the surface of the conic section produced by the cut 1 as indicated at *c* in Fig. 3, and also intersecting the surface of the theoretical hyperbola at station 35, at the point *d*, which 20 as seen before in certain cases lies at the bottom of the annular groove formed at this station. This operation is as indicated by the encircled numeral 2 in Figs. 2 and 3, and likewise gives to the larger end of the cone the shape of a true 25 conic frustum.

Thereafter, another straight taper is turned down on the surface thus imparted to the cone or casting in such manner that its small end intersects the cut 1 at station 17 as indicated 30 at the point *e* and hence has the same diameter as this cut at this station, and also intersects the cut 2 at station 27, as indicated at *f*, having at its large end the dimension of cut 2 at this point. This final cut is indicated by the 35 encircled numeral 3.

Obviously, in making a lot of identical cones, the second and succeeding ones of the series may be made by merely duplicating the measurements of the first, as through turning them with the use 40 of a former.

It is found in practice unnecessary to modify the shape of existing cones in regard to the portion of their length extending from station 0 to station 5, because the shape of the first five 45 inches at the small end of all known types of bottom cones used in roving frames departs in so slight a degree from a conic section, and because also the proximity of the unyielding surface of the bobbin prevents the pressure of the 50 presser from throwing the bobbin's growth out of step with the theoretical rate of increase in its diameter expressed by the hyperbola, when the winding is controlled by this portion of the bottom cone. In event the diagrammatic showing of the bottom cone in Figs. 1 to 3, in which 55 the curvature of the cones has been greatly exaggerated and intensified to make the departures of the invention more conspicuous, and which for the first five inches of the small end has not 60 been modified but is of hyperbolic conoidal shape, the relatively slight curvature of this portion of the hyperbolic cone will be apparent. In these figures, the true hyperbolic curvature is indicated by the dot-and-dash lines *g*, while the profile achieved through the practice of the invention 65 is indicated in solid lines.

It is to be noted that all the corrections applied to the theoretical or hyperbolic cone consist in cutting away the material of this hyperbolic cone, so that the resulting improved cone 70 has a belt-engaging surface less in diameter at substantially all points in its length than that of the hyperbolic conoid conforming to the theoretical percentage of increase in bobbin diameter. This is because the pressure of the press-

er and other factors make it necessary to reduce the angular speed of the bobbin by unequal amounts from the point in the winding where these forces make the thickness of the successive layers less than that of the roving being wound, through to the completion of the winding. Thus, the intermediate portions of the length of the improved cone have a diameter less than the diameter needed to impart a progressive reduction in bobbin rotation proportioned to equal additions to bobbin-diameter as produced by winding the successive layers. The basic concept of the improved cone as thus made becomes a series of truly conic frusta placed end to end in contiguous relation on a common axis, either with or without the inclusion of the old conoidal frustum at the small and less troublesome end of the cone.

The effect of the presser which makes necessary the modification of the theoretical hyperbolic conoidal bottom cone is represented graphically in Fig. 6. This is a diagrammatic plan view of the standard flyer *h* shown in operative relation with an empty bobbin *i* in Fig. 5. When the bobbin is empty, the presser *k* occupies the full-line position, in which its counter-balancing weight *m* swings about the axis of the bobbin *i* in a circle of radius *R*, the centrifugal force of the weight *m* overbalancing the similar force of the presser *k* and causing the latter to swing inward and press radially against the surface of the first layer wound on the bobbin *i* with maximum force. When the bobbin has grown to the diameter indicated by the circle *n*, the weight *m* will be travelling about the axis of the bobbin 100 on a smaller circle of radius *r*, the resultant lessened centrifugal force of this weight having decidedly diminished the force with which the presser now bears against the surface of the wound mass *n*.

Not only does the roving made through the use of cones embodying the invention show a conspicuous increase in uniformity, but also the use of the improved cones usually makes it possible to take out from one to two teeth from the 120 twist gear used, because of the uniformity of tension attained, and this means an increase in the rate of production of about 3% for every tooth removed.

While I have illustrated and described one good 125 method of practising the principles of the invention, I am aware that many modifications may be made therein by any person skilled in the art, without departing from the scope of the invention as expressed in the claims. Therefore, 130 I do not wish to be limited to the specific form shown, or to the particular details and dimensions of construction thereof, but

What I do claim is:—

1. The method of making paired cooperating 135 roving-frame cones which consists in applying thereto surfaces of rotation mutually representing complementary portions of a hyperbolic curve, and thereafter modifying the conoidal surface of one thereof by dividing the total length 140 into thirty-five equally spaced stations, applying a straight taper intersecting the hyperbolic conoidal surface at or about stations 5 and 25, applying a second straight taper intersecting the first straight taper at or about station 21 and the 145 hyperbolic conoidal surface at station 35, and then applying a third straight taper intersecting the first two straight tapers at or about stations 17 and 27.

2. In a roving frame, in combination, means for 150

- varying the speed of winding revolution of the bobbins comprising in combination a driving cone, a belt, and a driven cone having a belt-engaging surface of convex profile, less in diameter at substantially all points in its length than that of a hyperbolic conoid conforming to the theoretical percentage of increase in bobbin diameter.
3. In a fly-frame, in combination, means for varying the speed of winding revolution of the bobbins comprising in combination a driving cone, a driven cone, and intermediate driving connections varying the driving ratio between the two cones, at least one of such cones having a surface of convex profile, less in diameter at substantially all points in its length than that of a hyperbolic conoid conforming to the theoretical percentage of increase in bobbin diameter, to compensate for the effect of the presser on the rate of increase of bobbin diameter during the winding.
4. In a roving frame, in combination, a cone controlling the speed of winding rotation of the bobbins, having a series of contiguous conic frusta of different slopes and lengths presenting a profile made up of segments of straight lines of substantial length.
5. In a roving frame, in combination, means for equalizing the tension on the roving which includes the combination with feeding and winding devices, of a cone having a series of contiguous conic frusta of progressively larger size and diminishing angularity of slope with respect to their common axis.
6. In a roving frame, in combination, a cone controlling the winding speed of the bobbins, having a surface of convex profile comprising a series of conic frusta of different slopes and less in diameter at substantially all points than the diameter of the hyperbolic conoid conforming to the theoretical percentage of increase in bobbin diameter, combined with a convex hyperbolic conoid frustum.
7. In a roving frame, in combination, a cone controlling the winding speed of the bobbins, having a surface comprising a series of conic frusta of different slopes and lengths presenting a profile made up of segments of straight lines of substantial length, combined with a terminal hyperbolic conoid frustum.
8. In a roving frame, in combination, a pair of cones controlling the winding speed of the bobbins, one thereof having a series of contiguous conic frusta of different slopes and lengths presenting a profile made up of segments of straight lines of substantial length, and the other being a hyperbolic conoid.
9. In a roving frame, a cone controlling the winding speed of the bobbin comprising a terminal portion having at substantially all points in its length diameters adapted to produce a progressive reduction in bobbin-rotation proportionate to equal additions to bobbin diameter as produced by winding the successive layers, combined with intermediate portions of its length of convex profile and of diameters less at substantially all points in its length than that needed to impart a progressive reduction in bobbin-rotation proportionate to such equal additions.
10. In a roving frame having drawing, twisting and winding devices, the combination therewith of a pair of cones reducing the angular speed of the bobbin in accordance with its actual rate of increase in diameter as affected by the pressure of the presser, one of such cones having at substantially all points in its length a diameter lying between that of the hyperbolic conoid conforming to the theoretical percentage of increase in bobbin diameter without regard to the pressure of the presser, and that of a straight-taper cone of the same end-diameters and lengths as the conoid.
